UNITED STATES PATENT OFFICE.

GEORGE F. HURT, OF ATLANTA, GEORGIA, ASSIGNOR TO PRATT ENGINEERING & MACHINE COMPANY, OF ATLANTA, GEORGIA, A CORPORATION OF GEORGIA.

SULFUR-BURNING.

1,289,783.

Specification of Letters Patent. Patented Dec. 31, 1918.

Application filed July 14, 1917. Serial No. 180,517.

To all whom it may concern:

Be it known that I, GEORGE F. HURT, a citizen of the United States, residing at Atlanta, in the county of Fulton and State of Georgia, have invented certain new and useful Improvements in Sulfur-Burning, of which the following is a specification, reference being had therein to the accompanying drawing.

10 My invention relates to sulfur burning, that is, to a novel process and apparatus for such purpose, available, for example, for continuous operation in the combustion of brimstone, the products of which combustion can be treated to yield sulfuric acid.

The general objects of the improvement are to afford increased efficiency, as compared with heretofore known processes and apparatus, and improvement in output and economy when made use of for sulfuric acid manufacture or other practical purposes. Other general objects of my invention are the simplification, reduction in size and cheapening of the apparatus, rendering more simple, convenient and effective its observation and handling, and increasing its life and durability.

For convenience the part of the apparatus where the melted brimstone is converted into gases or vapors will be termed the burner, and the combustion which occurs at this point will be termed the burning of the material, although subsequently the combustion may resume or continue in a place which for convenience may be termed the combustion space; but there need be no clear line of division between the burner chamber and combustion chamber or space.

A particular object of the present improvement is to afford a very efficient and thorough burning operation of a comparatively small body or bulk of melted sulfur, caused to present in an effective way a very large superficial area of burning surface in the presence of a suitable supply of oxygen. As air forms the practical source of oxygen, I shall use the two terms interchangeably.

Another particular object is the conservation of the heat of combustion by so proceeding that the outgoing gases from the ap-

paratus will possess a higher and more uniform temperature than in heretofore known apparatus; thus increasing the concentrating and denitrating actions in the Glover tower and enhancing the output of sulfuric acid, 55 if used for such purpose, and also preventing sublimation of sulfur, which has heretofore frequently occurred in the passages, due to cooling of the gases.

Another particular object is to afford 60 easily performed and quickly responsive regulation of combustion or burning, thereby enabling intelligent correction of faulty conditions or results in the system, impossible with adjustment requiring considerable time 65 to take effect, owing to the arising of other errors and the difficulty of determining the effect of the correction. The lack of uniformity in heretofore known processes and apparatus has necessitated operating with a 70 low average percentage of sulfur oxids in the outgoing gases in order not at any time to exceed the permitted maximum; whereas the uniform regulation obtainable with the present invention permits a considerably 75 higher average sulfur content, and thereby much less bulky sulfuric acid making apparatus for a given output.

Other objects relate to matters of combination and arrangement, adjuncts, and features of design and construction. For example, I have provided a sulfur infeeding mechanism which is regular and positive in action, free from clogging, practically sealed against leakage or admission of air, and easy 80 of exact and close regulation during the running of the apparatus. Various other objects and advantages of the present invention will be elucidated in the hereinafter following description of one embodiment thereof, and further unmentioned advantages will be apparent to those skilled in the art to which the invention pertains.

To the attainment of the above objects and advantages the present invention comprises 85 the novel process for the burning or combustion of sulfur; the process of manufacturing sulfuric acid; and the novel burner or combustion apparatus, the sulfuric acid making apparatus embodying the same, and the 100

novel adjuncts, features of combination, design, construction, details and other features which are shown, mentioned or claimed herein.

5 In the accompanying drawings illustrating an example of how my invention may be practised, Figure 1 in elevation shows a general diagram of a plant for the manufacture of sulfuric acid and comprising a sulfur combustion apparatus embodying the present invention. The remaining figures show 10 only the parts of the sulfur combustion apparatus.

Fig. 2 is a longitudinal section taken generally on the plane 2—2 of Fig. 3, and showing a sulfur burner and combustion apparatus constructed in accordance with, and capable of carrying out, the present invention.

Fig. 3 is a partial front elevation and partial transverse section of the apparatus 20 shown in Fig. 2.

Fig. 4 is a longitudinal vertical section on the plane 4—4 of Fig. 3 showing the sulfur infeed.

25 Fig. 5 is a longitudinal vertical section showing one of the air blast devices, taken, for example, on the plane 2—2 of Fig. 3.

Fig. 6 is an inclined view of certain parts of Fig. 5 looking in the direction of the 30 arrow 6.

Fig. 7 is a partial view similar to Fig. 2 showing a modified form of burner chamber rear wall.

According to my invention, as regards the 35 burning of the sulfur, this, generally speaking, comprises maintaining a suitable body or pool of melted sulfur, which may be of comparatively small bulk, and producing what I may term surface-multiplying movement of the burning molten material in the presence of a suitable oxygen supply. Various ways may be employed for giving movement to the material to greatly increase its superficial area, and therefore effectiveness of burning; for example, herein is shown an operation consisting in spraying or scattering the melted sulfur in the form of a multitude of drops. This advantageous action not merely extensively enlarges the 45 exposed surface, but, by maintaining the material in rapid motion, prevents the formation of a stagnant envelop of sulfur dioxide, which would tend to impede the burning. This improvement, moreover, not merely effectively multiplies the active surface or 50 area, but permits its very easy and prompt regulation, for example, by adjusting the extent of the spraying movement. The spraying, for example, may be produced by 55 an upward blast of air introduced beneath the surface of the pool of melted burning sulfur, causing a fountain or spray of an extent depending on the quantity and pressure of air in the blast and the size, shape

and submergence of the nozzle. This air 6 furnishes oxygen, which takes part in the combustion, but may be supplemented by additional air supply. The liquid sulfur which is neither burned nor volatilized simply returns to the pool.

7 This novel burner and burning process are further advantageous in permitting the particular adjustment of the operation, to be described, which also constitutes a part of the present invention; also the effective readjustment or regulation of the burning operation to meet faults or difficulties observed in any portion of the process.

An important feature of my invention, and one which I believe is novel with me, comprises restricting the oxygen supply at the burner to substantially what is sufficient to burn only that fraction or portion of the sulfur whose combustion will suffice to volatilize the remainder, and such volatilized sulfur being later supplied with oxygen in the combustion spaces to continue the combustion, and thereby preserve an extremely high temperature to the outlet. Overheating at any point is thus prevented, and loss by conduction and radiation are minimized, so that the total heat or temperature is thoroughly conserved; and this action may be aided by employing insulating material in the walls of the apparatus. Conserving the high temperature prevents sublimation in manufacturing sulfuric acid, and, moreover, the very high temperature of the outgoing burner gases renders more effective and gives greater output to the sulfuric acid making process.

Supposing that between 20% and 30% of the sulfur is sufficient, on being burned, to volatilize the remaining 70% or 80% of the sulfur fed to the apparatus, my plan is to muffle the air supply at the burner, so that the total air is sufficient only to oxidize this 20% or 30%, the remainder becoming volatilized, and the total gaseous products passing to the combustion spaces, along which the combustion progressively proceeds by the admission of additional air, so as to complete the combustion before reaching the exit, while conserving the high temperature and heat, as already explained.

A prominent difficulty existing with prior processes has been the effective and intelligent regulation of operations. When some fault or difficulty has been observed at some part of the process or apparatus, the attempt to meet this by regulation has often proved futile, because of the delay in actually effecting a change of conditions by the supposed regulation, this delay being largely due to the inability to effect quick or sudden a considerable reduction or increase in the surface area of molten sulf

exposed to air. With my apparatus a quick adjustment and response is afforded, because I am able to coöperatively regulate both the superficial area of burning of the sulfur and the supply of air or oxygen thereto. Thus, the extent of the spray of burning sulfur can be immediately altered by appropriate valves, and this in connection with the alteration of the rate of auxiliary oxygen supply gives complete and prompt adjustment of burning operation, not merely for the purpose of insuring the conservation of temperature, as already pointed out, but for delivering outgoing gases of more uniform composition and temperature. The sulfur content in the outgoing gases of prior processes had to be kept at a very low average, owing to the extreme lack of uniformity, whereas with my invention the sulfur content can be raised substantially to the permitted maximum, thus greatly increasing the output of sulfuric acid for a plant of given size, or, on the other hand, permitting the size of the plant to be reduced for the given output.

Having thus described the nature of the process, I will now refer to the drawings and describe a specific apparatus embodying the invention, the operation and regulation of which will be subsequently explained.

In the accompanying drawings, above the ground level 10, is seen a sulfur burning or combustion apparatus 11, to which the novelty of the present invention more particularly relates. Since the novel features thereof are peculiarly advantageous in rendering more profitable the manufacture of sulfuric acid, I have diagrammatically indicated in Fig. 1 a complete sulfuric acid making plant. The combustion apparatus 11 is shown as having its exit leading to the Glover tower 12, from which in turn the course of the gases is through the chambers 13, and finally through the Gay-Lussac tower 14 to the escape or stack 15.

The combustion apparatus 11 is shown as comprising within the same outer walls a space or chamber containing the burner and other spaces, chambers or flues in which the combustion proceeds and is completed. The burner chamber and the combustion spaces might be separately constituted in some cases, and, in fact, my burner could be used with different forms of combustion apparatus, and might sometimes be useful without the operation of completing the combustion.

The burner and combustion spaces are inclosed within outer walls of brick 17 at the sides and top, which will preferably be bound together by heavy stays to preserve the shape of the apparatus. Also I provide an inner lining of fire brick 18, and preferably between this and the outer walls I introduce an insulating material of a refrac-

tory nature such as kieselghur. The arrangement of the interior may be as follows.

Behind the front wall is the burner chamber 20, and this is shown as separated by a fire brick bridge wall 21 from the first combustion space or chamber 22. The wall 23 to the rear of this is provided near the bottom with a passage 24, leading to the second combustion chamber 25, back of which is a second bridge wall 26, over which the gases may pass into the third and final combustion chamber 27. The wall 28 to the rear of this is provided with a passage 29 leading to a chamber 30, in which is shown a niter pot 31, provided for supplying nitrogen gases for the reactions to take place in the subsequent apparatus of the sulfuric acid making plant. Finally is the exit, or passage, or stack 32 at the rear, leading up to the lower end of the Glover tower 12. The length and volume of the combustion spaces, and the number of chambers and passes may be varied to suit the requirements of any particular case.

It will be noticed that my burner chamber 20 is much smaller than any burner chambers heretofore used, whereas the combustion chambers 22, 25 and 27 afford much greater combustion space than heretofore used. According to my process only a minimum portion of the sulfur is oxidized in the burner chamber, the remainder being merely vaporized, and the bulk of the combustion takes place in the combustion chambers, which for this purpose are provided with ample, but readily adjustable, oxygen or air admission ports 33. Thus, in the first combustion chamber are shown four air inlets at each side, and in the second combustion chamber two at each side, and each of the inlets is shown provided with a rotary draft regulator 34. The total length and volume of the combined combustion chambers is ample to permit complete combustion before the gases reach the niter chamber 30, and therefore there will be no flames in the niter chamber or in the flues beyond to cause deterioration. I prefer, however, to so adjust the regulators 34 as to admit the minimum amount of air to insure complete combustion and provide the air required for the later reactions, so as to yield burner gases having the maximum sulfur content.

The burner chamber 20 is provided with observation openings 39, so that the size and nature of the flames and operations may be examined as an assistance to effecting the desired adjustment and regulating the operation.

The burner chamber at its lower end is shaped to provide a pool 40 for the molten burning sulfur. This pool or basin contains a comparatively small body of material whose normal level is approximately at the

ground level 10. The pool is bounded or contained between the front wall 41, the two side walls 42, and either the slanting rear wall 43 of Fig. 2, or the stepped or benched wall 43 of Fig. 7; all of which are surfaced with fire brick, and the rear of which walls performs an operative function, as will be described.

The top surface of the molten sulfur in the pool 40 is so small as to be entirely inadequate for burning purposes, and the plan of my invention is to provide means for producing extensive increase of burning surface by giving what I have termed a surface-
10 multiplying movement to the burning sulfur in the presence of a suitable supply of oxygen, which, practically speaking, means air of combustion. This I accomplish, for example, by producing a spraying of the molten sulfur by means of an air blast from a nozzle 45, preferably submerged beneath the level of the pool and directed upwardly to forcibly drive the molten flaming sulfur upwardly into a fountain 46, in which the separate drops present an extremely large surface of combustion. By this means and because of the constant motion of the particles, which brings their surfaces into contact with fresh films of air, it is possible to cause burning and volatilization at a much
20 greater rate than would ever be needed in practice. Thus the two extremes are possible, that is, with the maximum blast the surface exposure and consequent burning and
25 volatilization would exceed practical needs, and without the blast there remains only the restricted top surface of the pool 40, which is below the practical needs. As will be explained, the ready and instant adjustment
30 of the blast and spray to any degree between these extremes is practicable with my invention.

The slanting or benched rear wall 43 or 44 serves the dual function of catching and returning to the pool the liquid sulfur, while at the same time exposing such liquid sulfur over the wall surface to further burning action. The returning liquid sulfur, fresh from the hot flames, serves to keep the pool in an extremely hot condition. This action is of great importance, and coupled with the small bulk of the pool and the constant circulation therein, entirely precludes any part of the liquid sulfur cooling to
50 where it may become viscous, which frequently happens with large or deep or insufficiently heated sulfur pools, causing frosting and sometimes compelling suspension of operation to cure the defect.

60 The air blast nozzle 45 is constructed of material of sufficiently refractory properties to withstand the heat of the pool. It is shown mounted at the end of a pipe 47 leading from the exterior. This pipe is shown connect-
65 ed to a circular plate or nozzle door 48, de-

tachably connected to a casting 49 embedded in the walls and having a corresponding circular opening. The attachment may consist of a plurality of latch levers 50 on the casting 49 adapted to be thrown into wedging contact with inclined cams or lugs 51 on the plate 48, so that quick detachment and replacement is possible when it is desired to remove an air blast nozzle. The plate 48 is formed with a hollow outward extension 52, to the outer side of which is coupled a pipe 53, provided with a globe valve or other suitable valve 54 for regulating the air flow and blast so as to adjust the spray of burning sulfur.

70 The spray nozzle 45 and fittings 47 to 54 described may be in multiple, and four complete spray devices are shown, which, having separate valves 54, are independently regulable. A single source of compressed air, such as compressor 56, may be employed, this serving to pump air into the equalizing air tank 57, from which the piping first leads to a point 58 within the apparatus above the first bridge wall 21, so as to heat the air
80 highly before supplying it to the blast. From this point the connections lead through a pipe 59, insulated as indicated at 60, to the several valves 54, and thence to the nozzles 45.

85 By employing air to produce the sulfur spray, this air augments the burning, but at times would be insufficient in itself for the desired burning operation, and I therefore prefer to provide an additional or supplemental supply of air, thereby making an adequate total, which, moreover, can be effectively regulated in quantity without disturbing the adjustment of the spray, namely, by varying the supplemental air supply. Thus,
90 for example, air ports may be provided at suitable points in the burner chamber, and I have shown two air ports 61 in the circular plate 48, each of them controllable by a gate or door 62, which may be adjusted to enlarge or diminish the port, so that the air drawn into the burner will be accordingly increased or diminished.

100 While only one burner chamber and one sulfur pool is herein shown, the principles could be applied with these in duplicate or multiple; for example, a division wall longitudinally through the middle of the burner chamber would give practically two burner chambers each with one pool, two burners or sprays, two auxiliary air inlets, etc., and the sulfur supply could be apportioned between the two.

105 While different forms of sulfur infeeding devices might be employed, I prefer one such as that herein illustrated, giving great regularity of feed of the powdered material, together with the ability to regulate the rate at will, and the ability to seal substantially the infeed opening against passage of air;

thereby permitting uniformity in the burning process and in the production of sulfur oxids.

The sulfur may enter at the front wall 5 through an inclined passage or chute 64, which terminates with a vertical drop by reason of a slight recess at 65.

The hopper 66 is entirely at the exterior and sufficiently spaced away from the walls 10 to preclude overheating. The combination and arrangement of parts, including the below-ground level of the pool, is such that the hopper 66 is near the ground, and therefore 15 easy of access and view, so that the workman is at all times able to observe the progress and condition of the sulfur feed, so that he may alter the rate of feed if he finds it to vary from the prescribed or predetermined rate.

20 Between the hopper and the inclined passage 64 is a movable compartment device or wheel 67. This is positive in action, being driven slowly at a uniform rate by a motor or other suitable device 68, acting through 25 belting 69, pulley 70, worm 71 and a worm wheel 72 on the shaft of the compartment wheel 67. Each compartment or pocket 73 as it passes the open bottom of the inclined throat of the hopper receives a full charge 30 of powdered or small sulfur, which is leveled off by a plate 74, so that the quantity dumped into the chute by each compartment will be uniform. The gate 74 is capable of 35 sliding vertically, thus avoiding clogging, as the gate can yield in case lumps are fed with the sulfur.

The rate of feed could be regulated by 40 altering the rate of rotation of the motor or of the compartment wheel, but for fine regulation I prefer the simple device of 45 adjustably altering the height of the slide plate 74, which can be done by introducing or removing a shim, distance piece, or liner 75, or replacing it by one of a different thickness, this being located between the rear top 50 wall of the hopper and an overhanging flange 76 on the slide plate, and thereby increasing the quantity discharged by each compartment of the wheel.

55 The workman bringing each weighed load of sulfur may wheel it up the incline of a ramp 77 by wheelbarrow, and thence dump it directly into the hopper 66.

For the purpose of removing ashes or impurities gathering at the surface of the sulfur, I am enabled by my invention to provide a very simple contrivance, consisting of an overflow gate or plug 78, engaging an aperture formed at 79 in one of the walls of 60 the burner chamber at substantially the level of the ground, so that by merely raising the level of the sulfur pool, as will be later explained, the surface material and ashes can be flowed out.

65 The operation of the described apparatus

may be substantially as follows, assuming, for example, that 1200 pounds of brimstone per hour are to be burned or converted into sulfuric acid. The powdered material may be supplied in a measured charge or barrow 70 once every ten minutes in the amount of 200 pounds. The infeeding mechanism may be set to feed at exactly this rate, although initially an additional charge should be introduced, so that the hopper will never become entirely empty, which would break the air seal and permit leakage of air and disturbance of the burning operation. I prefer to so adjust the infeed mechanism that 200 pounds will be introduced to the sulfur pool 75 in slightly less than ten minutes, say nine and a half minutes, the motor being thereupon stopped with a partial charge left in the hopper until the next 200-pound charge is dumped into the hopper, when the motor 80 is restarted after the lapse of a half minute. This slight interruption does not disturb the practical continuity of the process, and enables somewhat better check to be kept upon the sulfur feeding operation.

85 As soon as the sulfur has commenced to be infed into the burner chamber, it is ignited, the heat melting the sulfur, which as it melts increases in depth until the pool or basin is nearly full. It will be understood that a slight current of air is preliminarily introduced at the nozzles for the purpose of keeping them open and clear from solid or liquid sulfur. When the molten sulfur has risen to a level somewhat 90 above the tips of the air blast nozzles, the air will be turned on further, producing a spray, and shortly afterward the blast may be increased to its working pressure when the sulfur level has risen so that the nozzles 95 are submerged to the desired normal extent. When thus started into operation, the apparatus may be maintained running for a period of months, or even years, without substantial interruption.

100 The sulfur pool 40 tends to take its own proper depth and to therefore properly submerge the nozzles, that is to say, for any given adjustment of the air blast and supplemental air admission. If the level should momentarily be too high, the increased rapidity of burning would bring about the lowering of the level and decreased submergence, which in turn would diminish the rate of combustion, thus preserving a continual balance; which, moreover, can be observed and taken care of through adjustment of air by the attendant.

110 The sulfur dioxid, the volatilized sulfur, a small amount of sulfur trioxid and the 115 uncombined portion of the air pass from the burner chamber over the first bridge wall to the combustion spaces, which are of extended length and large volume, so that 120 suitable admission of air will cause the com- 130

pletion of the combustion of the volatilized and superheated unburned sulfur, at the same time maintaining the high temperature to the outlet.

5 According to my invention, by restricting the air, and thereby smothering the burner, so as to oxidize only sufficient sulfur to generate enough heat to volatilize the remainder, the air regulation is simplified; 10 since its only function is to gasify the entire amount of sulfur. My plan is rather to minimize the burning, contrarily to prior processes which attempted to completely oxidize the supplied sulfur at the burner, 15 and I leave the completion and bulk of the combustion to the subsequent stages, in the combustion flues, as explained.

So uniform an operation is possible with my invention, that in a case where the sulfur 20 contents of the burner gases should not exceed, say, 11%, I may operate continuously with a practically uniform 10% rate, whereas irregular variation in operation would necessitate a much lower average, and 25 therefore require acid chambers of correspondingly greater bulk. By my invention the output of sulfuric acid is increased, this being in part due to the greater temperature of the outgoing burner gases, 30 which in heretofore known processes is only sufficient to heat the acid from a brick packed Glover tower to about 278° F., whereas I am enabled to produce a temperature of 317° F. or more. Tests have indicated 35 that when sulfuric acid is manufactured in a given plant converted to my process, the output in tonnage is increased in some cases as high as 25%, without increased, but rather with decreased, expense 40 and care of operation.

The interruptions to the operation necessary in my process are inconsequential. There being four air blast inlets, any one of them may be removed for inspection or 45 repair and another substituted without practically interfering with operations.

The accumulations of ashes on the surface of the molten sulfur in the pool may readily be removed from time to time through the 50 discharge door or opening at the ground level. This will be done by first reducing the air supply to the nozzles to a negligible point, thus causing a gradual increase in the quantity of sulfur, the spray ceasing 55 and the level of the sulfur rising until the point is reached where the surface sulfur and all impurities can be run out through the discharge opening at the ground level, whereupon the opening may be closed and 60 burning conditions restored. No raking of floating ash is required, and the accumulating ashes do not impair the operations, because the air blast in the molten sulfur tends to form an open crater at the surface, and 65 all floating impurities constantly tend away

from this crater, so that they are not thrown up with the spray. On the rare occasions when heavy ash settles at the bottom of the pool, it may be raked out through a nozzle door, temporarily removed for the purpose. 70

It will be seen that this invention, in the form illustrated, employs a pool of melted sulfur interiorly located, within the burning chamber, and which is self-maintaining by reason of the burning action, and that there 75 is produced a fountain of liquid drops therefrom by an upward blast applied below the surface of the pool; and that the same is therefore the contrary of a proposed apparatus in which no interior sulfur pool 80 is maintained but an external supply of melted sulfur melted by a separate source of heat and injected in the form of a mist or atomized spray into the chamber.

It will thus be seen that I have described 85 an example of a process and apparatus for the burning of sulfur, or manufacture of sulfuric acid, and other features embodying the principles of the present invention. Since many matters of combination, design, 90 construction, detail and other features may be variously modified without departing from the underlying principles of the invention, there is no intention to limit the invention to such features except in so far as 95 set forth in the appended claims.

What is claimed is:

1. The process of burning sulfur, comprising maintaining a body of melted sulfur within the burning chamber and producing an extensive surface-multiplying movement of the burning material in the presence of a suitable oxygen supply. 100

2. The process of burning sulfur, comprising maintaining a body of melted sulfur 105 within the burning chamber, producing surface-multiplying movement of the burning material in the presence of a suitable oxygen supply, and regulating the area and rate of burning by adjusting the extent of such 110 movement.

3. The process of burning sulfur, comprising maintaining a body of melted sulfur within the burning chamber and producing a spraying or scattering movement of the 115 burning material in the presence of a suitable oxygen supply.

4. The process of burning sulfur, comprising maintaining a body of melted sulfur within the burning chamber, producing 120 a spraying or scattering movement of the burning material in the presence of a suitable oxygen supply, and regulating the same by adjusting the extent of the spray.

5. The process of burning sulfur, comprising maintaining a pool of melted burning sulfur, producing an upward spray thereof in the presence of a suitable oxygen supply and returning the liquid sulfur to 125 the pool. 130

6. The process of burning sulfur, comprising maintaining a body of melted sulfur and producing a spray of the burning material by a blast of air or oxygen applied within the body of sulfur. 5
7. The process of burning sulfur, comprising maintaining a body of melted sulfur, producing a spray of the burning material by a blast of air or oxygen applied within the body of sulfur, and supplying a supplemental supply of oxygen to the sprayed sulfur. 10
8. The process of burning sulfur, comprising maintaining a body of melted sulfur within the burning chamber, producing surface-multiplying movement of the burning material in the presence of a suitable oxygen supply, restricting the oxygen supply at the burner to substantially what is sufficient to burn the portion of the sulfur whose combustion will volatilize the remainder, and subsequently supplying oxygen to continue the combustion and maintain a high temperature to the outlet. 15

- 30
- 35
- 40
- 45
- 50
- 55
- 60
- 65
9. The process of burning sulfur, comprising maintaining a body of melted sulfur within the burning chamber, restricting the oxygen supply at the burner to substantially what is sufficient to burn the portion of the sulfur whose combustion will volatilize the remainder, and subsequently supplying oxygen to continue the combustion and maintain a high temperature to the outlet.
10. The process of burning sulfur, comprising maintaining a body of burning sulfur in a heat-insulated burning chamber, restricting the oxygen supply at the burner to substantially what is sufficient to burn the portion of the sulfur whose combustion will volatilize the remainder, and subsequently supplying oxygen to continue the combustion and maintain a high temperature to the outlet.
11. The process of burning sulfur, comprising maintaining a body of melted sulfur within the burning chamber, restricting the oxygen supply at the burner to substantially what is sufficient to burn that portion of the sulfur whose combustion will volatilize the remainder without excessive overheating, and subsequently supplying a sufficient quantity of oxygen to continue the combustion progressively.
12. The process of uniform sulfur burning comprising maintaining a pool of melted sulfur within the burning chamber and co-operatively regulating the superficial area of burning of the sulfur and the supply of oxygen thereto.
13. The process of uniform sulfur burning comprising maintaining a body of melted sulfur within the burning chamber, co-operatively regulating the superficial area of burning of the sulfur and the supply of oxygen thereto to burn and volatilize the sulfur at the rate fed, while restricting the oxygen supply at the burner to substantially that necessary to burn that fraction of the sulfur which will volatilize the remainder, whereby oxygen may be later supplied to complete the combustion. 70
14. The process of uniform sulfur burning comprising maintaining a body of melted sulfur within the burning chamber and producing surface-multiplying movement thereof, regulating the superficial area of burning of the sulfur by adjusting the extent of such movement, and co-operatively adjusting the supply of oxygen thereto. 75
15. The process of uniform sulfur burning comprising maintaining a body of melted sulfur and producing surface-multiplying movement thereof, regulating the superficial area of burning of the sulfur by adjusting the extent of such movement, and co-operatively adjusting the supply of oxygen thereto in such manner as to limit the burning to substantially that portion of the sulfur whose combustion will volatilize the remainder. 80
16. The process of burning sulfur, comprising maintaining a body of melted sulfur, producing a spray of the burning material by a blast of air or oxygen, and supplying a supplemental supply of oxygen to the sprayed sulfur under such restriction as to limit the burning to substantially the portion of the sulfur whose combustion will volatilize the remainder. 85
17. In an apparatus for burning sulfur, a burner chamber, means for maintaining a pool of burning liquid sulfur therein, means for producing surface-multiplying movement of the burning liquid sulfur, and sulfur combustion spaces beyond the outlet of said burner chamber. 90
18. In an apparatus for burning sulfur, a burner chamber, means for maintaining a body of burning liquid sulfur therein, means for producing surface-multiplying movement of the burning liquid sulfur by introducing an air blast beneath the surface, to spray the molten material, and sulfur combustion spaces beyond the outlet of said burner chamber. 95
19. In an apparatus for burning sulfur, a burner chamber, means for maintaining a body of sulfur therein, means for producing surface-multiplying movement of the burning sulfur by introducing an air blast beneath the surface, to spray the molten material, and means for supplying additional air of combustion. 105
20. In an apparatus for burning sulfur, a basin for containing a small molten sulfur pool with inadequate top surface, means for supplying sulfur to maintain such pool, means for producing an extensive surface-multiplying movement of the liquid burning material to afford adequate burning 110
- 115
- 120
- 125
- 130

surface, and sulfur combustion spaces beyond the outlet of said burner chamber.

21. In an apparatus for burning sulfur, a basin for a pool of molten sulfur, a refractory nozzle submerged in the melted material slightly below its surface and directed upwardly, whereby a forcible fountain of liquid drops may be produced, air connections for introducing a blast through said nozzle, a burner chamber containing said basin and shaped to return the unburned liquid material to the pool, and sulfur combustion spaces beyond the outlet of said burner chamber.

15 22. In an apparatus for burning sulfur, means for maintaining a body of molten burning sulfur, a plurality of submerged nozzles in the molten material, means for producing blasts at said nozzles for spraying the burning material, and means for separately adjusting the action of the several nozzles.

23. In an apparatus for burning sulfur, means for maintaining a body of molten burning sulfur, a plurality of submerged nozzles in the molten material, means for producing blasts at said nozzles for spraying the burning material, and means detachably fitting each nozzle to the apparatus whereby it may be removed without shutting off the other nozzles.

24. In an apparatus for burning sulfur, a burner chamber adapted to contain a body of molten sulfur, means for producing a variable spray for extensively multiplying and regulating the superficial area of the molten sulfur therein, means for cooperatively regulating the air admitted thereto, and sulfur combustion spaces beyond the outlet of said burner chamber.

40 25. In an apparatus for burning sulfur, a burner chamber, means for maintaining a body of sulfur therein, means for producing surface-multiplying movement of the burning sulfur by introducing an air blast beneath the surface, to spray the molten material, means for supplying additional air of combustion, and means for cooperatively regulating the air admitted thereto.

50 26. In an apparatus for burning sulfur, a basin for a pool of molten sulfur, a nozzle and air connections for introducing a blast beneath the surface of the pool, means for adjusting the amount or pressure of air delivered to said nozzle, and means for adjustably admitting further air cooperatively with the extent of the sulfur spray.

60 27. In an apparatus for burning sulfur, a burner chamber for containing a sulfur pool, a readily attachable and detachable plate in the wall thereof, a pipe passing through said plate and having a nozzle piece submerged in the sulfur pool for producing a spray of burning material, and adjustable

air ports in said plate for admitting air to the chamber.

28. In an apparatus for burning sulfur, a burner chamber for containing a sulfur pool, a readily attachable and detachable plate in the wall thereof, a pipe passing through said plate and having a nozzle piece submerged in the sulfur pool for producing a spray of burning material, means for supplying air at adjustable pressure to said nozzle, and adjustable air ports in said plate for admitting air to the chamber.

29. In an apparatus for burning sulfur, a burner chamber designed to contain a pool of molten burning sulfur, means to supply sulfur thereto, means to produce a spray of the sulfur within the chamber for causing extensive multiplication of surface of combustion, means to supply air of combustion at a rate restricted substantially to what is sufficient to burn that portion of the sulfur whose heat of combustion will volatilize the remainder of the sulfur, and sulfur combustion spaces beyond the outlet of said burner chamber.

30. In an apparatus for burning sulfur, a burner chamber designed to contain a pool of molten burning sulfur, means to supply sulfur thereto, means to produce a spray of the sulfur within the chamber for causing extensive multiplication of surface of combustion, means to smother the burner action by restriction of air supply so that the sulfur passing from the burner will be largely unburned but volatilized, and sulfur combustion spaces beyond the outlet of said burner chamber.

31. In an apparatus for burning sulfur, a burner chamber designed to contain a pool of molten burning sulfur, means to supply sulfur thereto, means to produce a spray of the sulfur within the chamber for causing extensive multiplication of surface of combustion, means to supply air of combustion at a rate restricted substantially to what is sufficient to burn that portion of the sulfur whose heat of combustion will volatilize the remainder of the sulfur, and large combustion spaces beyond the burner having air admission for completing the combustion.

32. In an apparatus for burning sulfur, a burner chamber designed to contain a pool of molten burning sulfur, means to supply sulfur thereto, means to produce a spray of the sulfur within the chamber for causing extensive multiplication of surface of combustion, means to smother the burner action by restriction of air supply so that the sulfur passing from the burner will be largely unburned but volatilized, and large combustion spaces beyond the burner having air admission for completing the combustion.

33. In an apparatus for burning sulfur, a burner chamber designed to contain a pool

of molten burning sulfur, means to supply sulfur thereto, means to produce a spray of the sulfur within the chamber for causing extensive multiplication of surface of combustion,

5 means to supply air of combustion at a rate restricted substantially to what is sufficient to burn that portion of the sulfur whose heat of combustion will volatilize the remainder of the sulfur, and large combustion spaces beyond the burner having air admission for completing the combustion, said burner chamber and combustion spaces being heat insulated.

34. In an apparatus for burning sulfur, 15 a burner chamber, means for maintaining a pool of sulfur therein, means for producing an extensive surface-multiplying movement of the burning sulfur, means for smothering the burner action by restricting air supply 20 so that a large part of the sulfur passing out will consist in unburned volatilized sulfur, and sulfur combustion spaces beyond the outlet of said burner chamber.

35. In an apparatus for burning sulfur, 25 a burner chamber, means for maintaining a body of sulfur therein, means for producing surface-multiplying movement of the burning sulfur by introducing an air blast beneath the surface, to spray the molten material, means for supplying additional air of 30 combustion, and means for smothering the burner action by restricting air supply so that a large part of the sulfur passing out will consist in unburned volatilized sulfur.

35 36. In an apparatus for burning sulfur, a pool of molten sulfur, a nozzle and air connections for introducing a blast beneath the surface of the pool, means for smothering the burner action by restricting air supply 40 so that a large part of the sulfur passing out will consist in unburned volatilized sulfur, and sulfur combustion spaces beyond the outlet of said burner chamber.

37. In an apparatus for burning sulfur, 45 the combination of a sulfur burner adapted to present a large superficial area of the molten material, said burner comprising a burner chamber shaped to maintain an internal pool of melted burning sulfur, means for supplying air thereto in such restricted quantities as to smother the burning action, whereby the outgoing gases will contain a large proportion of volatilized sulfur, and combustion spaces of extended volume and 50 length provided with adjustable air inlets, whereby the volatilized sulfur will be completely oxidized.

38. The process of burning sulfur comprising maintaining a pool of melted sulfur 60 within the burner chamber, and producing therefrom in the presence of oxygen a fountain of the melted sulfur.

39. The process of burning sulfur comprising maintaining a pool of melted sulfur

within the burner chamber, and producing 65 therefrom in the presence of oxygen a fountain of the melted sulfur by an upward blast applied below the surface.

40. The process of burning sulfur comprising maintaining a pool of melted sulfur 70 within the burner chamber, producing therefrom in the presence of oxygen a fountain of the melted sulfur, and maintaining the pool at a non-viscous temperature by the heat of the burning.

41. The process of burning sulfur comprising maintaining a pool of melted sulfur within the burner chamber, producing therefrom in the presence of oxygen a fountain of the melted sulfur, and returning to the 80 pool the unburned unvolatilized sulfur.

42. The process of burning sulfur comprising maintaining a pool of melted sulfur within the burner chamber, producing therefrom in the presence of oxygen a fountain 85 of the melted sulfur, and regulating the burning by coöperatively adjusting the extent of the fountain and supply of oxygen.

43. The continuous process of burning sulfur comprising maintaining a pool of melted 90 sulfur within the burner chamber by feeding regulated quantities of sulfur thereto, producing from such pool in the presence of oxygen a fountain of the melted sulfur by an upward air blast within the pool, returning to the pool the unburned and unvolatilized hot sulfur of the fountain, admitting oxygen for combustion, drawing off the 95 products of combustion, and regulating the burning by adjusting the extent of fountain, 100 supply of oxygen, or both.

44. The continuous process of burning sulfur comprising maintaining a pool of melted sulfur within the burner chamber by feeding regulated quantities of sulfur thereto, 105 producing from such pool in the presence of oxygen a fountain of the melted sulfur by an upward air blast within the pool, returning to the pool the unburned and unvolatilized hot sulfur of the fountain, admitting 110 oxygen for combustion, drawing off the products of combustion, and regulating the burning by adjusting the extent of fountain, supply of oxygen, or both, in such way that the outgoing products contain more volatilized than burned sulfur. 115

45. The continuous process of burning sulfur comprising maintaining a pool of melted sulfur within the burner chamber by feeding regulated quantities of sulfur thereto, 120 producing from such pool in the presence of oxygen a fountain of the melted sulfur and supplying such restricted quantities of oxygen that only a fraction of the outgoing sulfur content is burned, and the remainder volatilized by the heat of combustion. 125

46. In an apparatus for burning sulfur a burner chamber adapted to hold a pool of

- melted sulfur, an air blast means located below the pool surface for producing within the chamber from such pool a fountain of melted sulfur, and sulfur combustion spaces 5 beyond the outlet of said burner chamber.
47. In an apparatus for continuous burning of sulfur, a burner chamber adapted to hold a pool of melted sulfur, means for producing within the chamber from such pool 10 a fountain of melted sulfur, means for sup-

plying raw material and oxygen for combustion to the chamber in regulated quantities whereby the burning may be restricted, and large combustion passages beyond the chamber having oxygen supply for combustion of the volatilized sulfur content of the outgoing products.

In testimony whereof, I have affixed my signature hereto.

GEORGE F. HURT.
